UNITED STATES PATENT OFFICE

158,692

BRASSIÈRE

William Rosenthal, Bayville, N. Y.

Application October 29, 1949, Serial No. 5,786

Term of patent 14 years

(Cl. D20—4)

To all whom it may concern:

Be it known that I, William Rosenthal, a citizen of the United States, residing at Bayville, Nassau county, New York, have invented a new, original, and ornamental Design for Brassières, of which the following is a specification, reference being had to the accompanying drawing, forming part thereof:

Fig. 1 is a front perspective view of a brassière, showing my new design, and

Fig. 2 is a rear perspective view thereof as it appears in unfastened position.

I claim:

The ornamental design for a brassière, substantially as shown.

WILLIAM ROSENTHAL.
